WOOD HEEL GROOVING MACHINE

Edwin A. Webster, Atkinson, N. H., assignor of
one-half to Earl F. Webster, Newton, N. H.

Application January 7, 1933, Serial No. 650,646

30 Claims. (Cl. 12—47.1)

This invention primarily relates to that type of wood heel grooving machines, or machines for forming the breast surface of a wood heel, in which the lip portion of the heel, which meets 5 the shank part of the shoe when in position thereon, is curved convexly from one side to the other, at the time the grooving operation is performed, the convexly curved surface being blended with the rest of the breast surface which is 10 formed.

Prior to my invention this result has been accomplished in two generically different ways; 1st by moving the heel in a curved path, with relation to a rotary cutter, as in the patent to Sanders 15 No. 1,213,271, and 2d by operating on the heel by means of a cutter of the internal, or "rosette" type, as in the patent to Russ No. 1,846,615.

Trade requirements demand numerous variations in the formation of the breast surfaces of 20 wood heels, many, but not all of which may be secured by varying the contour of the cutting edges of the cutter blades. For example, a variation in the formation transversely of the groove, or from side to side of the heel, cannot be secured 25 by a variation in the cutter blades, in fact, variations of this character cannot, so far as I am aware, be secured with machines produced prior to my invention. Variations in the convexity of the lip may be secured, in the type first mentioned, by varying the length of the arc through 30 which the heel holder is carried, and in the internal cutter type, by providing for a radial adjustment of the blade holding means, but both of these arrangements involve objectionable complications.

The objects of my invention are, primarily, to provide a machine for performing the above described heel-grooving operation, which is adapted 40 for ready adjustment to secure all necessary variations of convexity of the lip, and the longitudinal inclination of the breast surface, without changing the shape of the cutter blade edges, and which in addition may be arranged to secure any desired variation in the transverse formation of 45 the breast surface. Also to provide a machine with which the grooving operation may be made almost wholly automatic, so that the operation may be greatly facilitated, without danger of injury to the operator.

50 I accomplish these objects primarily by mounting a rotary cutter, of the type commonly employed for wood heel grooving directly on the shaft of an electric motor, and by pivotally mounting the entire motor so that it may be oscillated about 55 an axis which is approximately perpendicular to

the motor axis, to carry the cutter back and forth in operative relation to a fixed heel holder, and providing in connection therewith means for oscillating the motor at a desired speed, the supporting means of the motor being arranged for adjustment with relation to the heel holder and the cutter with relation to the supporting means, to vary the length of the radius of the path of movement of the cutter, and to vary the inclination of the plane of movement of the motor axis. 10 Also by providing means for bodily moving the supporting means of the motor towards or from the holder during the oscillating movement, when variations in the transverse formation of the groove are desired. 15

For a more complete disclosure of the invention reference is made to the following specification in connection with the accompanying drawings, in which:

Fig. 1 is a view in side elevation of a complete 20 machine embodying my invention.

Fig. 2 is a plan view thereof.

Fig. 2^a is a detail view of an alternative construction for controlling the position of the motor oscillating shaft. 25

Fig. 3 is a view in elevation of the front end of the machine.

Fig. 4 is a detail sectional view of a portion of the blank feeding means.

Fig. 5 is a detail view of the motor oscillating 30 means.

Figs. 6 and 7 are detail views of the motor supporting and adjusting plates.

Figs. 8 and 9 are detail views of the clamping member of the blank holder, or jack. 35

Figs. 10 and 11 are detail views of the base member of the jack.

Fig. 12 is a detail view of the operating means of the jack clamping member.

Fig. 13 is a detail view of a heel-positioning, 40 notch-forming means.

Fig. 14 is a detail view of the breast gage operating means.

Figs. 15, 16 and 17 are views of heel blanks illustrating the work performed thereon by the 45 machine.

As shown in the drawings, a motor 10 is mounted on the base of the machine and is arranged to drive a counter shaft 12 by a belt 11, and the shaft 12 is in turn arranged to drive a shaft 14 50 through a belt 13. Shaft 14 is provided with a worm 15, which is in mesh with a worm gear 16 mounted on a shaft 17, which may be considered as the main shaft of the machine. The shaft 17 has a crank arm 18 secured on one end thereof, 55

and arm 18 has a crank pin 19 on which one end of a connecting rod 20 is mounted, the opposite end of said rod being journaled on a crank pin 21 which is secured in a crank arm 22 on a shaft 23, 5 said crank pin 21 being somewhat elongated to permit longitudinal adjustment of shaft 23 without disturbing the connection with connecting rod 20. Shaft 23 is journaled in bearings 24 formed on a base plate 25, which is mounted for 10 vertical adjustment on an upright 26 on the machine base, said adjustment being effected by an adjusting screw 27 which is swiveled in a bracket 28 secured on the upright 26 and threaded in said plate 25, clamping bolts 29, which pass thru slots 15 in the plate, being provided for holding the plate securely in adjusted position.

In this connection, also, means are provided for securing a longitudinal adjustment of shaft 23, which comprise a collar 39, mounted on, and having a swivel connection with said shaft, said collar having an adjusting screw 31 swiveled therein, which is threaded in a boss 32 on the bearing 24. The purpose of this adjustment will be hereinafter explained, as will an alternative means shown in Fig. 2a.

A crank arm 34 is rigidly mounted on the front end of shaft 23 at right angles thereto, and has a supporting plate 35 formed integrally therewith and extended forwardly therefrom at right angles, 30 and said plate 35 has a flat face 36, (see Fig. 6), on its side next shaft 23, which is disposed in a plane parallel to the axis of shaft 23. An adjusting plate 37 is mounted on said face 36 and is connected to plate 35 by a bolt 38, which is extended through a hole 39 in plate 37, and a hole 40 in plate 35, and said plate 37 is provided with dovetail guideways 41, in which the base plate 42 of an electric motor 43 is mounted, (see Figs. 5, 6 and 7), an adjusting screw 44 being threaded in 45 a lug on plate 37 and engaged with base plate 42, to adjust the latter in said guideways 41, and bolts 45 being provided in plate 37 to clamp plate 42 in the positions to which it is adjusted in said guideways. A bolt 46 is extended from plate 37, 45 through an arc-shaped slot 48 in plate 35, having bolt 38 as its center, to clamp the plates 36, 37 and 42 together, the above described construction permitting adjustment of motor 43 in the plane of the face 36 and in a direction parallel to the 50 axis of the shaft 59 of the motor 43, and also a swinging adjustment about the bolt 38 as a center. In practice, in all positions of adjustment of motor 43, its shaft 59 is held in a position in which its axis intersects the axis of shaft 23, either at 55 right angles, or at an angle which is slightly inclined from a right angle, as indicated in Figs. 1, 2 and 5. The motor 43 is connected to a suitable electric terminal 51 by a flexible cable 52, and a rotary heel grooving cutter 53, having suitably shaped blades, is mounted on the end of the 60 motor shaft 59.

As thus arranged the main body of the motor is so supported that much the greater portion of the weight thereof is supported beneath the level 65 of the axial line of shaft 23, and the shaft 50 thereof is extended above said level, so that the cutter 53 is supported at a substantial distance above said line, and oscillation of the shaft 23 will cause the cutter to be swung back and forth 70 in a curved path about the axis of shaft 23 as a center. The crank arm 22 on shaft 23 is of considerably greater length than that of crank 13, so that, when the shaft 17, is driven by the motor 19, the rotary movement thereof will be converted 75 into an oscillatory movement of shaft 23, there-

by producing an oscillatory movement of cutter 53. The terminals of the path of movement of the cutter may be somewhat varied by varying the length of the connecting rod 29, which is provided with means for this purpose, but this adjustment having once been made will not ordinarily have to be disturbed. 5

It will thus be apparent, that if a heel blank is held so that its breast portion protrudes into the path of movement of the cutter, a breast surface will be formed on the blank which will have a convexly curved lip portion, as shown in Fig. 15, the center of revolution of which will be at the axis of the shaft 23. 10

In connection with the above described grooving means, suitable heel blank holding means are provided, which hold the blank in a fixed position with relation to the cutter as it is swung from right to left, as viewed in the position of Fig. 3, automatic means, hereinafter described, being provided for feeding the blank into position to be operated on, for clamping it in this position while the cutter is moved from right to left, and for unclamping it and removing it from this position before the cutter is swung back from left to right, and then for discharging the blank which has been operated on into a suitable chute at the front of the machine. 15 20 25

This means is operated in time with the oscillation of the motor shaft 50, and comprises the following mechanism:—

A fixed clamping member 55, or base member of the jack, which is adapted to receive the base end of the heel blank, is mounted on the frame in a horizontal position, in which it will support the blank in the correct position to be operated on by the cutter 53, as it moves from right to left, and a support 56, having a horizontal top surface, is provided directly in front of member 55, on which the operator deposits the blank at the beginning of the operation. A clamping member, in the form of a plunger 57, is mounted for vertical reciprocation in the frame, and has a lever 58 pivotally connected to the upper end thereof, said lever being mounted on a pivot 59 in the frame and having a rod 60 connected at its upper end to the opposite end thereof from the plunger, the lower end of rod 60 being engaged with one arm of a bell crank lever 61, which is mounted on a pivot 62 and has a cam roll 63 in the other arm thereof, arranged to engage a cam 64 fixed on the front end of shaft 17, so that, on each revolution of the latter, the plunger 57 will be moved down to clamping position and raised to an initial position, the weight of the parts acting to hold the roll 63 in contact with the cam 64. The force with which a blank is clamped may be varied, and adjustments made to correspond to blanks of different height by varying the length of the plunger 57, or of the rod 60, or both, adjusting means for this purpose being shown.

In this connection I provide means for automatically moving the blank from the support 56, where it is deposited by the operator, into position to be clamped by the plunger 57, and operated on by the cutter, and then for removing the blank in advance of the return movement of the cutter, and depositing it in a discharge chute. 65

For this purpose I provide a mechanism partly shown in detail in Figs. 4 and 12, which comprises an arm 65, mounted on a rock shaft 66, journaled in the frame and having an arm 67 which is connected to one end of a connecting rod 68, the opposite end thereof being connected

to an arm 69, mounted on a rock shaft 70, journaled in the frame, said shaft having an arm 71 thereon, in the end of which a cam roll 72 is mounted, said roll being arranged to engage a cam 73, on shaft 17, and being held in contact therewith by a spring 74, whereby the arm 65 is swung back and forth on each revolution of shaft 17. The arm 65 has a holder block 75 on its end, in which a friction pin 76 is reciprocally mounted, 5 said pin being retarded in its reciprocating movements in both directions by a friction packing 77, which engages a flat face on one side of the pin 76 and is adjusted by a screw 78. A finger 80 is mounted on a pivot 81, in one side of block 75, and is provided with a hook 82 at one end, the opposite end having an arm 83, the end of which is convexly curved, and which bears against one side of the pin 76, the latter having a longitudinally extending recess 84 therein into which the arm 83 will be swung by the action of a spring 10 pressed pin 85, when the pin 76 is reciprocated, as hereinafter described.

A movable breast gage 86 is provided, shown in detail in Figs. 13 and 14, which is mounted on a lever 87, pivoted at 88 on the frame in position to raise and lower said gage at the inner end of the base member 55 of the jack. A connecting rod 89 is attached, at one end, to said lever 87 and the opposite end thereof is pivotally 15 connected to an arm 90, on a rock shaft 91, mounted in the frame, said shaft having an arm 92 thereon having a cam roll 93 which is held in engagement with the periphery of a cam 94 on shaft 17. By this arrangement the gage 86 is raised and lowered, in time with the other 20 operations, on each revolution of shaft 17.

For the purpose of guiding the heel blank as it is moved from the support 56 to the base member 55 of the jack, and for positioning it laterally thereon, a T-shaped bracket is provided, the base 25 portion 95 of which is connected to the frame by a bolt 96, which passes through a slot 97 in the frame, (see Figs. 8, 10 and 11), permitting longitudinal adjustment of said base portion. 30 As shown in Fig. 10, a flat, elongated guiding portion 98 is formed on the end of said base portion 95, and extends at each side thereof from a point in proximity to the path of oscillation of the cutter 59, at right angles to said path, 35 and forwardly at one side of the jack member 55 and the support 56, said guiding portion 98 having a vertical face next said member and support, in which a dovetail groove is formed, to receive a strip of fiber board 99, which extends 40 throughout the length thereof and protrudes slightly beyond the end of the portion 98 into a position in which it may be trimmed by the cutter to the shape of the groove to be formed in the blank, thereby serving to reinforce the side 45 of the blank at which the cutter emerges, so as to prevent splintering of the wood. A spring 50 pressed guiding finger 100 is supported at the opposite side of the member 55 from the guiding portion 98, and acts to guide the blank as it is pushed inward, and to hold it against the fiber 55 guiding plate 99.

The whole operation of feeding the blank into position, and removing it, is as follows:—

The operator places a heel blank *x* on the support 56, as shown in Fig. 1, then arm 65 is swung 60 down and rearward and pin 76 engages the back side of the blank and pushes it rearward onto the base member 55. Before the blank reaches its extreme inward position, the breast gage 86 is moved up into position, so that the breast of the 65

blank is pressed against it. At the same time the plunger 57 will be descending, and just before the head of the plunger engages the blank, a spring pressed pin 101, in the head (see Fig. 9) 70 will engage the blank, so that, just before the blank is clamped, it will be yieldingly pressed by the pin 76 against the gage 86, by the finger 100 against the vertical face formed by the fiber board plate 99, and by the spring pressed pin 101 against the base member 55, so that the blank 75 will be accurately positioned, and then the blank will be firmly clamped against the base member 80 by the plunger 57 in position to be operated on by the cutter. As the cutter is advanced, the breast gage is quickly moved down out of the path of the cutter, and then the grooving operation will 85 be performed. The downward and rearward movement of the arm 65 continues during the grooving operation, causing the pin 76 to be pushed back, and the finger 80 to be advanced, 90 so that, by the time the cutter has been swung past the blank and the grooving operation finished, the inner inclined end of the recess 84 in the pin 76 will engage the arm 83 of the finger 80, causing the latter to be swung towards the blank, 95 so that it will be held in the dotted line position of Fig. 4, in which position the hook 82, at the end of the finger, will be swung in front of the blank, so that it is in position to engage the breast surface formed by the cutter. At this instant the plunger 57 is lifted out of contact with the blank and then the arm 65 is swung back, causing the finger 80 to pull back the blank while holding the same against the face of the fiber plate 99. A chute 102 is arranged at the front 100 end of support 56 and plate 99, in position to receive the blank as it is pulled back from the jack by finger 80, so that it will be automatically discharged. As the arm 65 swings back to its initial position, the rear end of pin 76 is forced against 105 a fixed stop plate 103, which is adjustably mounted on a bracket 104, causing the pin to be pushed back to its initial position, as shown in Fig. 1, so that the operation above described may be repeated.

In the subsequent operation of heel turning, in which the sides of the heel are formed, it is necessary that the heel be held centrally with relation to the breast surface which is formed by the grooving operation, so that the center of the convexly formed lip, or the highest point therein 110 with relation to the base surface, will be equidistant from the two sides, at the points where they meet the breast surface.

For the purposes of positively locating the blank 115 in the heel turning machine with reference to the breast surface which is formed, as shown in Fig. 15, means are provided herein for forming a positioning groove *y* (see Figs. 15, 16) in the base portion of the heel blank. To this end a right 120 angularly shaped lever 105 is mounted on a pivotal support 106 at the front end of the machine, and one arm of said lever has a cam roll 107 therein, which is held in contact with a cam 108, on the shaft 17, by a spring 109. The other arm 125 of said lever has a shaft 110 mounted therein, having a pulley 111 on one end thereof and an electric motor 112 is mounted on the machine base and arranged to drive shaft 110 constantly by means of a belt 113. A drill 114 is mounted in a 130 chuck in the opposite end of said shaft, and a stop screw 115 is arranged on lever 105, in position to engage the frame, and limit the swinging movement of the lever by the spring 109. As thus arranged, as the lever 105 is swung rearward by the 135

spring 109, the drill 114 is advanced into engagement with the underside of the blank while it is held clamped in the jack and forms the inclined groove, or notch y in the base side of the 5 lip of the blank, as shown in Fig. 13, the cam 108 permitting the spring 109 to move the lever 105 so as to perform this operation practically at the instant the blank is clamped by the plunger 57, and acting to withdraw the drill by the time 10 the breast gage 86 is withdrawn to permit the grooving operation. For the purpose of permitting the drill to perform this operation while the blank is clamped in the jack at this time, the base member 55 of the jack has a notch 115 15 formed in the middle of its front end and on its under side (see Fig. 10), and the breast gage 86 is also provided with a notch 88', to permit this operation to be performed before the gage is withdrawn.

20 The above described construction and arrangement permits various adjustments to be made so that different formations of breast surface may be secured without changing the formation of the cutting edges of the cutter blades. If it is desired to increase the convexity of the lip curvature, the shaft 23 will be raised by adjusting the bearing plate 25 upwardly, and then the base plate 42 will be correspondingly lowered on the plate 37, and if the convexity is to be decreased, the 25 shaft 23 will be lowered and the motor adjusted upward on plate 37. An adjustment to vary the thickness of the lip which is formed on the blank may be made by adjusting the plate 42 on the plate 37, without substantially varying the convexity, but if it is desired to correct any variation 30 in convexity made by such an adjustment, such correction may be made by adjusting the bearing plate 25, adjustments to vary the thickness of the lip and adjustments to vary its convexity being in 35 no way related.

40 A further variation of the formation of the breast surface may be made by varying the inclination of the axis of the cutter shaft to the axis of the shaft 23, which intersects it at approximately right angles. This may be done by 45 loosening the nut on the clamping bolt 46, so that a swinging adjustment of the plate 37 may be made about the bolt 38, as a center. This adjustment principally affects the inclination of the breast surface adjacent the top lift, or tread 50 end of the heel, with relation to the tread surface.

55 As, with the above described construction, it is not practical to vary the position of the base member 55 of the jack, a further adjustment, which varies the depth of the groove which is formed in the blank, may be made by adjusting the shaft 23 longitudinally by means of the adjusting screw 31, thereby varying the position of 60 the path of movement of the cutter, so that it will be carried closer to, or further away from the blank which is held on the jack.

65 As shown in detail in Fig. 2^a, means may be provided, in substitution for the adjusting screw 31 and parts engaged thereby, whereby the shaft may be moved longitudinally during the grooving operation, so that the depth of the groove which is formed will be varied transversely of the heel instead of forming it at a uniform depth, as 70 has been done by all prior machines of this character.

75 When this arrangement is to be employed, the screw 31 will be removed and a collar 116, having a cam path 117 therein, will be secured on the shaft 23. A bracket 118 will be attached to the

bearing plate 25, said bracket having a pin 119, extending into said cam path 117, so that, as the shaft 23 is oscillated in one direction, it may be moved longitudinally away from the blank during the first half of the movement from right to left, and towards it during the remaining portion of the movement. This longitudinal movement will be timed with respect to the period during which the cutter is actually engaged with the blank, so that the change in direction of movement will take place at the middle of the grooving operation. An illustration of a formation which may thus be secured is shown in Fig. 17, on which the blank x' is shown as having two distinct breast faces divided by a medial line extending from the lip to the tread face. Obviously, various formations in this way may be made by varying the formation of the cam path 117, as for example, the entire breast surface may be made transversely convex similarly to the formation of the lip surface. Various ornamental effects may thus be produced. Obviously, also, the longitudinal adjustment of the shaft 23, which is secured by the screw 31, might also be secured by the construction shown in Fig. 2^a, if the cam path was not curved, but the screw adjustment is preferably where no variation in the transverse formation is desired.

The machine organized as above described, performs the work rapidly and satisfactorily, 30 without danger of injury to the operator, and is adapted to vary the formation of the heel breast in several respects, without varying the formation of the cutter blades.

I claim:

1. In a machine for grooving heel blanks, a fixed blank holder, a constantly rotating grooving cutter, and means for moving said cutter past the holder in a curved path about an axis transverse to the axis of the cutter, to perform 40 a grooving operation on a blank held by the holder.

2. In a machine for grooving heel blanks, a fixed blank holder, a constantly rotating grooving cutter, and means for oscillating said cutter 45 in operative relation to the holder about an axis transverse to the axis of the cutter.

3. In a machine for grooving heel blanks, a fixed blank holder, a shaft having a rotary grooving cutter thereon, means for constantly rotating 50 said shaft, and means for simultaneously swinging said shaft about an axis intersecting the axis of the shaft at approximately right angles, to carry the cutter past the holder in operative relation therewith.

4. In a machine for grooving heel blanks, a fixed blank holder, a shaft having a rotary grooving cutter thereon, means for constantly rotating said shaft, means for simultaneously swinging said shaft about an axis intersecting 60 the axis of the shaft, to carry the cutter past the holder in operative relation therewith, and means for varying the angular relation between the axis of the shaft and the axis about which it is swung.

5. In a machine for grooving heel blanks, a fixed blank holder, a shaft having a rotary grooving cutter thereon, means for constantly rotating said shaft, means for simultaneously swinging said shaft about an axis intersecting the axis of 70 the shaft, to carry the cutter past the holder in operative relation therewith, and means for varying the distance between the cutter and the axis about which it is swung.

6. In a machine for grooving heel blanks, a 75

- stationary blank holder, a motor having a shaft arranged to be constantly rotated thereby, a grooving cutter mounted on said shaft, a support on which said motor is mounted, and means for oscillating said support about an axis which intersects said shaft, to carry said cutter past said holder in operative relation thereto and to return it to an initial position.
7. In a machine for grooving heel blanks, a stationary blank holder, a motor having a shaft arranged to be constantly rotated thereby, a grooving cutter mounted on said shaft, a support on which said motor is mounted, and means for oscillating said support about an axis which intersects the axis of said shaft at approximately right angles, to carry the cutter past the holder in operative relation therewith.
8. In a machine for grooving heel blanks, a stationary blank holder, a motor having a shaft arranged to be constantly rotated thereby, a grooving cutter mounted on said shaft, a support on which said motor is mounted, means for oscillating said support about an axis which intersects the axis of said shaft at an angle, to carry said cutter past said holder in operative relation thereto, and means to adjust said support relative to the axis about which it is oscillated to vary the curvature of the path of movement of the cutter.
9. In a machine for grooving heel blanks, a fixed blank holder, a shaft having a grooving cutter thereon, means for constantly rotating said shaft, a support for said shaft arranged for oscillation about an axis which intersects the axis of said shaft, means for adjusting said support transversely of its axis with relation to said holder, and means for adjusting said cutter with relation to the axis of said support, to vary the curvature of the path of movement of the cutter with relation to the holder.
10. In a machine for grooving heel blanks, a fixed blank holder, a shaft having a grooving cutter thereon, means for constantly rotating said shaft, a support for said shaft arranged for oscillation about an axis which intersects the axis of said shaft, means for oscillating said support to carry the cutter in a curved path past the holder in operative relation therewith and to return the cutter to an initial position, means for adjusting said support, to vary the position of its axis with relation to the holder, and means to adjust the cutter in the direction of its axis and with relation to the axis of said support.
11. In a machine for grooving heel blanks, a fixed blank holder, a shaft having a grooving cutter thereon, means for constantly rotating said shaft, a support for said shaft arranged for oscillation about an axis which intersects the axis of said shaft, means for oscillating said support to carry the cutter in a curved path past the holder in operative relation therewith, and means to adjust said support in the direction of its axis, to vary the transverse position of the path in which the cutter is carried with relation to the holder.
12. In a machine for grooving heel blanks, a blank holder, a rotary grooving cutter, means for moving said cutter past the holder in a direction transversely of a blank held by the holder, to perform a grooving operation on the blank, and means for moving said holder and cutter relatively in opposite directions transversely of said direction, to vary the depth of the groove transversely of the blank as the grooving operation is performed.
13. In a machine for grooving heel blanks, a blank holder, a rotary grooving cutter, means for moving said cutter past the holder in a predetermined path to perform a grooving operation on a blank held in said holder, and means for simultaneously moving said holder and cutter relatively in a direction transverse to said path, to vary the depth of the groove transversely of the blank.
14. In a machine for grooving heel blanks, a blank holder, a rotary grooving cutter, means for moving said cutter past the holder in a predetermined path to perform a grooving operation on a blank held in said holder, and means for simultaneously moving said cutter relatively to said holder in a direction transverse to said path, to vary the depth of the groove while being formed.
15. In a machine for grooving heel blanks, a fixed blank holder, a rotary grooving cutter, means for oscillating said cutter back and forth past said holder in a curved path, to perform a grooving operation on a blank held in said holder, and means for moving said cutter in the direction of its axis of oscillation while it is operating on the blank, to vary the depth of the groove while being formed.
16. In a machine for grooving heel blanks, a fixed blank holder, a shaft having a grooving cutter thereon, means for constantly rotating said shaft, a support for said shaft arranged for oscillation about an axis which intersects the axis of said shaft, means for oscillating said support to carry said cutter back and forth past the holder in operative relation therewith, and means to move said support in the direction of its axis during the operative movement of the cutter.
17. In a machine for grooving heel blanks, a fixed blank holder, a constantly rotating grooving cutter, means for oscillating said cutter about a fixed axis as it is rotated, to move the same in one direction in operative relation to the holder and to return it to an initial position, means for automatically clamping a blank in said holder in advance of the operative movement of the cutter, and means for automatically unclamping the blank and for removing it from the holder in advance of the return movement of the cutter.
18. In a machine for grooving heel blanks, a fixed blank holder, a constantly rotating grooving cutter, means for oscillating said cutter about a fixed axis as it is rotated, to move the same in one direction in operative relation to the holder and to return it to an initial position, means for automatically feeding the blank into the holder and for clamping it in position therein after the cutter has been moved past the holder during its return movement and before it has been moved into operative relation therewith during its operative movement, and means for automatically unclamping the blank and for removing it from the holder after the cutter has been moved out of operative relation with the holder and before it is moved past the holder on its return movement.
19. In a machine for grooving heel blanks a fixed blank holder, a supporting shaft and means to move the same rotatively, an arm extending from said shaft having a support thereon extending in parallelism with the shaft, a motor mounted on said support, a shaft in said motor arranged to be rotated thereby and held in a position in which its axis is intersected by the axis of said supporting shaft at an angle, and a grooving cutter on said motor shaft arranged to be

carried thereby in operative relation with said holder, to perform a grooving operation on a blank held by said holder as it is moved past the same by the rotative movement of said supporting shaft.

5 20. In a machine for grooving heel blanks, a fixed blank holder, a rotary grooving cutter, means to move the cutter past the holder to perform a grooving operation on a blank held by said holder, an auxiliary cutting device, and means to move said device in time with the movement of the cutter to form a positioning notch in the base side of the lip portion of the blank while held in said holder.

10 21. In a machine for grooving heel blanks, a blank holder, a rotating grooving cutter, and means for moving said cutter in a curved path transversely of its axis past the holder while held in a fixed position, to perform a grooving operation on a blank held by the holder.

15 22. In a machine for grooving heel blanks, a blank holder, a rotating grooving cutter and means for moving said cutter past the holder while held in a fixed position in a path extending transversely of the cutter's axis and transversely 25 of the blank held by the holder, to perform a grooving operation on the blank.

20 23. In a machine for grooving heel blanks, a fixed blank holder, a rotating grooving cutter, means for moving said cutter back and forth past the holder to perform a grooving operation on a blank held thereby, and means for automatically clamping the blank in the holder in advance of the operative movement of the cutter and for automatically unclamping the blank to permit its removal from the holder in advance of the return movement of the cutter.

25 24. In a machine for grooving heel blanks, a fixed blank holder, a rotating grooving cutter, means for moving said cutter back and forth past the holder to perform a grooving operation on a blank held thereby, and means for automatically feeding the blank to the holder and for clamping it therein in advance of the operative movement of the cutter and for automatically unclamping the blank and removing it from the holder in advance of the return movement of the cutter.

30 25. In a machine for operating on wood heel blanks, a fixed blank holder member, a rotating cutter, means for moving said cutter past said member, to perform a breast shaping operation on a blank held thereby, and for returning the cutter to an initial position, a breast gage, automatic

means for moving said gage into operative relation with said holder member, means for clamping the blank in position thereagainst, and means for then moving the gage from its operative position in advance of the operative movement of the cutter.

35 26. In a machine for operating on wood heel blanks, a fixed blank holder member, a rotating cutter, means for moving said cutter past said member, to perform a breast shaping operation on a blank held thereby, and for returning the cutter to an initial position, a breast gage, automatic means for moving said gage into operative relation with said holder member, means for feeding the blank onto said member and into position 40 against said gage, means for clamping the blank thereon as positioned, and means for then moving said gage out of operative relation with the member in advance of the operative movement of the cutter.

20 27. In a machine for grooving heel blanks, a blank holder, a rotating grooving cutter, means for moving the cutter and holder relatively to perform a grooving operation on the breast portion of a blank held by the holder, an auxiliary cutting device, and means for operating the same in time with said grooving operation, to form a positioning recess in the base portion of the blank.

25 28. In a machine for grooving heel blanks, a blank holder, a rotating grooving cutter, means for moving the cutter and holder relatively to form a transversely extending groove and a transversely convex lip on the breast portion of a blank held by the holder, an auxiliary cutting device, and means for moving the same in time with the operative relative movement of the cutter and holder, to form an elongated positioning recess in the base side of the lip which is centrally located with relation to its side edges.

30 29. In a machine for operating on heel blanks, a fixed blank holder, a rotating cutter, and means for moving the cutter past the holder to perform a breast shaping operation on a heel blank held thereby.

35 30. In a machine for shaping the breast surface of heel blanks, a holder arranged to engage the ends of the blank, a rotating cutter and means for moving said cutter in a path extending transversely of the cutter axis past a blank held 45 in a fixed position by the holder from one side to the other thereof, to perform the breast shaping operation.

EDWIN A. WEBSTER.
